UNITED STATES PATENT OFFICE

EUGENE SCHWARZ, OF ALEXANDRIA, INDIANA, ASSIGNOR TO THE MANTLE LAMP COMPANY OF AMERICA, OF CHICAGO, ILLINOIS, A CORPORATION OF ILLINOIS

DESIGN FOR A LAMP SHADE

Application filed December 22, 1932. Serial No. 46,550. Term of patent 3½ years.

To all whom it may concern:

Be it known that I, EUGENE SCHWARZ, a citizen of the United States of America, residing at Alexandria, in the county of Madison and State of Indiana, have invented a new, original, and ornamental Design for Lamp Shades, of which the following is a specification, reference being had to the accompanying drawing, forming a part thereof.

The figure is a view in elevation of a lamp shade, showing my new design.

The shade is substantially of frusto-conical contour, while the surface ornamentation is substantially the same when viewed from the opposite side to that shown in the figure.

I claim:

The ornamental design for a lamp shade, substantially as shown and described.

In testimony whereof, I affix my signature.

EUGENE SCHWARZ.
